US0D1010109S

(12) **United States Design Patent** (10) **Patent No.:** **US D1,010,109 S**
(45) **Date of Patent:** **** Jan. 2, 2024**

(54) **URINE COLLECTION DEVICE**

(71) Applicant: **Sage Products, LLC**, Cary, IL (US)

(72) Inventors: **Brian J. Ecklund**, McHenry, IL (US);
Kristin M. Sexton, Lake in the Hills, IL (US); **Alex D. Kea**, Chicago, IL (US); **Daniel R. Ulreich**, Cary, IL (US)

(73) Assignee: **Sage Products, LLC**, Cary, IL (US)

(**) Term: **15 Years**

(21) Appl. No.: **29/699,144**

(22) Filed: **Jul. 23, 2019**

(51) **LOC (14) Cl. 24-02**

(52) **U.S. Cl.**

USPC **D24/122**

(57) **CLAIM**

The ornamental design for urine collection device, as shown and described.

DESCRIPTION

FIG. 1 is a perspective view of an embodiment of a urine collection device showing our new design.

FIG. 2 is a top plan view of the urine collection device of FIG. 1.

FIG. 3 is a bottom plan view of the urine collection device of FIG. 1.

FIG. 4 is a first side elevation view of the urine collection device of FIG. 1.

FIG. 5 is a second side elevation view of the urine collection device of FIG. 1.

FIG. 6 is a third side elevation view of the urine collection device of FIG. 1; and,

FIG. 7 is a fourth side elevation view of the urine collection device of FIG. 1.

The portions of the drawing shown in broken lines represent environmental aspects and form no part of the claimed design.

1 Claim, 5 Drawing Sheets
